Primary Examiner — L. A. Grabenstetter

(57) **CLAIM**

The ornamental design for a smartphone, as shown and described.

DESCRIPTION

1.-5. Smartphone

1.1 : Front

1.2 : Back

1.3 : Left

1.4 : Right

1.5 : Top

1.6 : Bottom

1.7 : Perspective

1.8 : Front, shown in a use state

1.9 : Perspective, shown in a use state

2.1 : Front

2.2 : Back

2.3 : Left

2.4 : Right

2.5 : Top

2.6 : Bottom

2.7 : Perspective

2.8 : Front, shown in a use state

2.9 : Perspective, shown in a use state

3.1 : Front

3.2 : Back

3.3 : Left

3.4 : Right

3.5 : Top

3.6 : Bottom

3.7 : Perspective

3.8 : Front, shown in a use state

3.9 : Perspective, shown in a use state

4.1 : Front

4.2 : Back

4.3 : Left

4.4 : Right

(Continued)

4.5 : Top
4.6 : Bottom
4.7 : Perspective
4.8 : Front, shown in a use state
4.9 : Perspective, shown in a use state
5.1 : Front
5.2 : Back
5.3 : Left
5.4 : Right
5.5 : Top
5.6 : Bottom
5.7 : Perspective
5.8 : Front, shown in a use state
5.9 : Perspective, shown in a use state
